POST INSULATOR TIE OR SIMILAR ARTICLE

James P. Markham, Webster St., Milford, N.H. 03055

Filed Dec. 24, 1968, Ser. No. 15,109

Term of patent 14 years

Int. Cl. D8—03

U.S. Cl. D8—230

FIG. 1 is a front elevation view of my post insulator tie or similar article;

FIG. 2 is a right side elevation view of FIG. 1;

FIG. 3 is a rear elevation view of FIG. 1;

FIG. 4 is a left side elevation view of FIG. 1;

FIG. 5 is a top plan view of FIG. 1; and

FIG. 6 is a bottom plan view of FIGURE 1.

The broken lines showing a typical insulator and conductor cable are for illustrative purposes only.

I claim:

The ornamental design for a post insulator tie or similar article, substantially as shown and described.
